UNITED STATES PATENT OFFICE.

EDWARD H. KRUSE, OF FORT WAYNE, INDIANA.

SUPPORT FOR OUTLET-BOXES.

1,354,309.

Specification of Letters Patent.

Patented Sept. 28, 1920.

Application filed December 17, 1917. Serial No. 207,476.

To all whom it may concern:

Be it known that I, EDWARD H. KRUSE, a citizen of the United States of America, and resident of Fort Wayne, in the county of

5 Allen and State of Indiana, have invented certain new and useful Improvements in Supports for Outlet-Boxes, of which the following is a specification.

This invention relates to improvements in 10 supports for outlet-boxes of that class ordinarily employed in electrical wiring installations. The object of the improvement is to afford means for adjustably positioning and securing the outlet-box, and also to afford 15 such structure for securing the box to a supporting bar that will admit of the use of ordinary stock retaining bolts, there being means provided for engagement in the slotted heads of the screws to prevent their 20 turning.

The object of the invention is accomplished by the construction illustrated in the accompanying drawings, in which:—

25 Figure 1 is an elevation partially in section showing the invention in mounted position;

Fig. 2 is a top plan view of the device in connection with an outlet-box;

30 Fig. 3 is a side elevation showing a modified form of the securing clamp with the bolts and their retaining device in connection therewith; and

Fig. 4 is a plan view of Fig. 3.

35 Similar characters of reference indicate corresponding parts throughout the several views and referring now to the same:—

It is the intention to secure the outlet-box 40 A to a cross-bar B that is fastened to the under faces of the joist C of the building in any suitable manner, and to effect the attachment of the outlet-box, a clip is provided. The clip is constructed from a metallic plate and is formed with a base D adapted to extend between the outlet-box A 45 and the supporting-bar B, and also with a tongue E shaped to fit over the bar B. A bolt F extends through the tongue and projects into the box A so that one of the ears G of the fixture-stud H may be secured 50 thereby. The rear end of the clip is secured by another bolt I which passes through its

base and extends into the box so that another of the ears G of the stud may also be secured.

The rear end J of the base D is turned 55 over the head of the bolt I with its extreme end extending into the slotted head of the bolt so that the latter is thereby held permanently in connection with the base and also from having turning movement. The outer 60 end K of the tongue E is likewise bent over the head of the bolt F with its extreme end extending into the slotted bolt-head so that it is also held in fixed position in the tongue and prevented from having turning movement. 65

In Figs. 3 and 4 is shown a modified form of clip and retaining means for the bolts. In this instance M is the base and N the tongue. The retaining means for the 70 bolts consists of a separate strip P through which each of the bolts Q—Q' extend. The opposite ends of the strip are turned over with their respective ends bent over the heads of the corresponding bolts and with 75 their extremities extending into the slots of the bolt-heads so that the bolts are thereby held in fixed position and are prevented from having turning movement.

In utilizing the invention the clip is placed 80 upon the supporting-bar with the latter extending between the tongue and base. The bar is then permanently secured in any suitable manner to the joist of the building. The outlet-box is then positioned in place 85 with the bolts extending thereinto, and is secured by applying the nuts L onto the bolts. In the event a fixture-stud is to be employed, it is positioned also upon the bolts before the nuts are applied, and is subsequently secured thereby together with the outlet-box. The clamping action of the tongue when the nut on the bolt F is tightened rigidly holds the clip, box and stud 90 fixedly to the supporting bar. Before being tightly secured, the box together with the clip and stud may be adjustably shifted lengthwise on the bar to the desired location. 95

What I claim is:—

In a device for mounting outlet-boxes, a 100 supporting bar; a clip having a base and tongue; and two bolts having slotted heads,

2
one of which extends through the base and
the other through the tongue, the respective
ends of the base and tongue being bent over
the heads of the corresponding bolts with
their extremities extending into the slotted
heads thereof, said bar being adapted to be
clamped between the tongue and base when
the outlet-box is secured upon said bolts.

In testimony whereof I affix my signature,
in presence of two witnesses.

EDWARD H. KRUSE.
